UNITED STATES PATENT OFFICE.

WILLIAM E. HALE, OF FORT WASHINGTON, PENNSYLVANIA, ASSIGNOR TO R. H. BEAUMONT CO., OF PHILADELPHIA, PENNSYLVANIA, A CORPORATION OF PENNSYLVANIA.

COAL AND ASHES HANDLING SYSTEM.

Application filed November 5, 1928. Serial No. 672,775.

The present invention relates to such a system having a skip hoist bucket and a car either with or without a hopper arranged for operation between the two, and the principal object of the present invention is to electrically insure the proper operation of each in conjunction with the other, or otherwise stated, to provide such a system in which the bucket of an electrically operated skip hoist will automatically move to the limits of its travel while an electrically propelled car will automatically move to the limits of its travel and in which the bucket will not dump unless dump receiving means are in proper position or condition for the reception of its contents.

The invention may be said to comprise the combination of a skip hoist, electrically operated with provisions to automatically reverse the bucket at the limits of its travel, and an electrically operated car running automatically back and forth on a horizontal track and conveying material elevated by the skip bucket. The car may receive material direct from the skip bucket or from a hopper into which the skip bucket discharges. In the latter case a gate is used on the hopper which is operated by the car in its last few feet of travel back to the leading point. The car is provided with a gate or door on the bottom opened upon contact with a device which can be placed along the track at any selected point to open the gate or door to discharge the load preferably on the outward trip. The door or gate is automatically closed before reaching the loading point. The motor for operating the car may be mounted on it or may operate by means of ropes or cables. In cases where the car receives its load direct from the skip bucket an electrical device operates in such a way that unless the car is in loading position the skip bucket will stop before dumping its load and will proceed again as soon as the car is in loading position. In cases where the car receives its load from a hopper into which the skip bucket discharges a switch device is employed to stop the skip bucket when the hopper is full until the car has taken enough material from the hopper to give room for a skip bucket full of material. The fundamental combination is of a skip hoist bucket and car driven by separate

means with connections made electrically to insure the proper operation of each in conjunction with the other.

The invention may be further said to comprise a coal and ashes handling system having in combination a skip hoist, means for moving the bucket of the skip hoist to the limits of its travel thereby dumping it, provisions adapted to stop the bucket short of dumping position, dump receiving devices, and equipment responsive to the dump receiving devices and adapted to make said provisions inoperative when the dump receiving devices are in receiving condition.

The invention further comprises the improvements to be presently described and finally claimed.

In the following description reference will be made to the accompanying drawings forming part hereof and illustrating an embodiment of the invention chosen from other embodiments and in which

Figure 1 is a diagrammatic elevational view of portions of a skip hoist electrically operated to the limits of its travel and of an electrically operated car running on a track and receiving material from the bucket of the skip hoist, showing also diagrammatically parts of connections for insuring the proper operation of each in conjunction with the other and

Fig. 2 is an elevational view illustrating a portion of the skip hoist and car with a hopper interposed between them and constituting the dump receiving device instead of the car as in Fig. 1.

Referring more particularly to Fig. 1, 1, generally is a skip hoist of which the bucket 2 is under normal conditions electrically operated to automatically reverse the direction of motion of the bucket at the limits of its travel. The cable *a* is a part of the means for moving the bucket to the limit of its travel thereby dumping it. 3 is an electrically operated car running back and forth on a horizontal track 4, and when in loading position receiving material elevated by the skip bucket and when in another appropriate position automatically dumping that material. The cable *b* is a part of the equipment for moving the car. As described the car 3 receives its load direct from the skip bucket 2, and electrical provisions and equipment are provided to prevent the

bucket from dumping if the car is not in loading position to receive the dumped material. 5 is a switch operated by the passage of the bucket to control the machinery which operates the bucket in such a way that the bucket is stopped before it dumps. 6 is electrical equipment actuated when the car is in loading position to nullify the stopping effect of the device 5 and permit the bucket 2 to travel far enough to dump into the car. 7 is a means for opening the gate 8 of the car to dump its contents and the element 7 may be placed along the track 4 at any desired point within the limits of travel of the car, and when it contacts with the arm 9 extending from the gate 8, the latter is automatically closed, for example, by gravity. It might be sufficient to say that the switch 5 is normally closed and is opened by the passage of the bucket, that the switch 6 is normally open and is closed by the car only when in or near loading position, and that these switches 5 and 6 are in parallel relation across the circuit which, when interrupted, stops the bucket and which, when closed, continues the travel of the bucket. Therefore if either one or the other of the switches 5 and 6 is closed, the bucket proceeds, but if the car is not in loading position the switch 6 is open and when the bucket in its movement opens the switch 5, the movement of the bucket is arrested and the switch 5 is timed to be opened by the bucket before the latter dumps. However, if the switch 6 is closed by the presence of the car in loading position, the circuit remains closed and the bucket goes to the limit of its travel although in doing so it opens the switch 5.

40 The switch 34 is arranged along the track in position to cause the car 3 to be started toward loading position.

The construction and mode of operation

of the apparatus shown in Fig. 2 is substantially as has been described except as follows: The skip bucket 2 dumps into a hopper 71 which in turn dumps into the car 3. The car 3 by the means 72 opens the hopper gate 73, which is self-closing when the car starts outward. In this case the switch 6' is operated to open automatically when the hopper 71 is full and should not have any more coal dumped into it to break the circuit which has been described and so stop the bucket when it opens switch 5. For this purpose there is in the hopper a flap 74 pivoted at 75 and turned by the coal in the hopper into position for opening the switch 6' as shown in Fig. 2. In this case the car 3 is driven back and forth from loading to dumping position and its driving connections need not be electrically interconnected with the driving provisions of the skip hoist.

The term coal and ashes in the claim is used to include any material which the system can handle.

It will be obvious to those skilled in the art to which the invention relates that modifications may be made in details of construction, arrangement and mere matters of form without departing from the spirit of the invention which is not limited to such matters or otherwise than as the prior art and the appended claim may require.

I claim:

In a coal and ashes handling system the combination of a skip hoist, means for moving the bucket of the skip hoist to the limit of its travel thereby dumping it, provisions adapted to stop the bucket short of dumping position, dump receiving devices, and equipment responsive to the dump receiving devices and adapted to make said provisions inoperative when the dump receiving devices are in receiving position.

WILLIAM E. HALE.
